UNITED STATES PATENT OFFICE.

JAMES GILLESPIE AND MARTIN GILLESPIE, OF WEST POINT, OHIO.

ROTARY ENGINE.

SPECIFICATION forming part of Letters Patent No. 268,659, dated December 5, 1882.

Application filed September 26, 1882. (Model.)

To all whom it may concern:

Be it known that we, JAMES GILLESPIE and MARTIN GILLESPIE, of West Point, in the county of Columbiana and State of Ohio, have 5 invented a new and Improved Rotary Engine, of which the following is a full, clear, and exact description.

This invention relates to the class of rotary engines provided with radially-moving gates 10 or pistons; and it consists in the combination and arrangement of parts, substantially as hereinafter more fully set forth.

Reference is to be had to the accompanying drawings, forming a part of this specification, 15 in which similar letters of reference indicate corresponding parts in both the figures.

Figure 1 is a side elevation of our improved engine with the face-plate removed and partly 20 sectional. Fig. 2 is a transverse section on line xx , Fig. 1.

A is the case or cylinder of the engine, provided with movable face-plates B B, which are formed with boxes for the shaft C, which passes transversely through the cylinder. The 25 central portion of the cylinder is removed to form the steamway, which is circular above the two points 1 1 at opposite sides, the center of the circle being at the shaft C; but below the two points 1 1 the steamway is flattened 30 or drawn inward eccentric to the shaft. In the bottom of the cylinder, and communicating with the steamway, are two ports, b b, for supplying steam; and at the lower end of these ports is fitted a rocking valve, c, which 35 is slotted for admitting steam to either port, according to the position of the valve, and thereby turning the engine in one direction or the other.

Upon the shaft C is a wheel, D, fitted with 40 sliding gates E, which may be two or more in number. These gates are fitted in grooves d in the wheel D, and are formed at their outer ends with T-flanges e, which, when the gates are moved inward, fit snugly in a recess formed 45 for them in the face of the wheel. At the edges of these recesses are grooves f, which allow the entrance of steam beneath the T-flanges of the gates.

h h are plates covering the steamway at 50 each side of the wheel D, and attached to the

wheel for rotation therewith. These plates are formed with grooves i, for receiving the edges of the sliding gates, so as to guide them in their movement and retain them in place when projected outward. k is an exhaust-port at 55 the upper part of the cylinder. The diameter of the wheel D is such that its under side moves in contact with the bottom of the steamway, and the enlargement of the steamway at the upper side of the wheel is sufficient to allow 60 the extreme movement required for the gates.

In operation, steam being admitted by one of the ports b, the gate E, in advance of the port, is forced outward by the steam entering the groove f beneath the flange of the gate, 65 so that the gate forms an abutment for receiving the steam-pressure, and the wheel is carried around. The gate reaches its extreme outward movement at the point 1, and remains in that position from that point to the exhaust- 70 port, where the steam is exhausted, and the pressure being at that moment taken by the other gate, the first one is moved readily inward by the eccentric surface of the steamway until it reaches the under side of the wheel, in 75 position for again receiving steam. In this manner a continuous rotation is obtained, and the parts being retained in position by the steam-pressure, no springs or other devices that are liable to get out of order are required. 80

Having thus described our invention, we claim as new, and desire to secure by Letters Patent—

In a rotary engine, the combination, with the cylinder or case A, having the steam-ports 85 b b and exhaust-port k, of the eccentric D, having the steam-grooves f f, arranged upon the sides of V-shaped sockets therein, said sockets terminating in guiding-grooves d, the side-projecting peripheral plates h, fastened to 90 the eccentric D, and provided with radial grooves i, and the pistons or gates E, provided with T-heads e, and sliding in the grooves d i, substantially as and for the purpose set forth.

JAMES GILLESPIE.
MARTIN GILLESPIE.
